UNITED STATES PATENT OFFICE

121,018

DESIGN FOR A MILL DISPENSER

Louis Pataky, Florissant, Mo.

Application March 18, 1940, Serial No. 91,027

Term of patent 3½ years

To all whom it may concern:

Be it known that I, Louis Pataky, a citizen of the United States, residing at Florissant, in the county of St. Louis and State of Missouri, have invented a new, original, and ornamental Design for Mill Dispensers, of which the following is a specification, reference being had to the accompanying drawing, forming part thereof.

I claim:

The ornamental design for a mill dispenser, as shown.

LOUIS PATAKY,
